UNITED STATES PATENT OFFICE

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS

LADDER FOR RAILWAY CARS

Application filed June 20, 1928. Serial No. 286,359.

My invention relates to improvements in ladders for railway cars, and has for its objects the provision of a safe, simple and inexpensive ladder structure which may be manufactured as a self-contained unit and applied to the car in its assembled form.

As is well known to those familiar with the conditions under which railway freight cars are operated, trainmen are often required to board cars at night-time, when trains are in motion and are often called upon to perform their duties under adverse weather conditions when such hazards as rain, sleet, ice, snow or intense cold have to be contended with. For the convenience of trainmen, side and end ladders are placed on each diagonal opposite corner of freight cars, the side ladder being provided with a footstep immediately below the same, and the respective ladders on each corner of car are placed adjacent to each other for the purpose of permitting trainmen to pass from the side to the end ladder or vice versa, but in practice such ladders are usually spaced inwardly from the corner of the car thereby making it necessary for a man to reach around the corner of the car and feel for the adjacent ladder, and in so doing he is liable to slip and fall from the car. It is therefore an object of my invention to remedy such deficiencies by an improved ladder structure embodying in a self-contained unit a combined side and end ladder which will obviate the necessity of a train man reaching around the corner of the car to locate the adjacent ladder and which will provide a vertical corner grip member common to both the side and end ladders.

Another object of my invention is to provide a ladder stile common to both a side and an end ladder and having a side footstep arranged immediately adjacent the said ladder stile.

Another object of my invention is to improve the ladder structure of that class of cars usually termed house or box cars, wherein side and end horizontal roof hand holds are placed on the roof of the car adjacent thereto. My improvements in this respect contemplate the use of a vertical corner member common to both the side and end ladder,

which not only provides a hand grip throughout the height of the ladders but is extended upwardly beyond the uppermost rungs of said ladders and deflected inwardly towards the roof handholds, for the purpose of bridging the space intermediate the vertical ladders and roof handholds and for the guidance and assistance of trainmen in passing from or to the top of the car by way of either the side or end ladder.

A still further object of my invention is to provide a ladder structure which will project outwardly beyond the end of the car thereby placing the footstep well in advance of the adjacent journal box of the truck, so that adequate clearance is afforded to permit the journal box lid to be swung upwardly without interference with the footstep or ladder parts.

A specific object of the invention is the provision of a corner stile member which will provide a footstep at its lower end, a hand grip at its upper end and a series of hand grips intermediate said footstep and upper hand grip.

Another specific object of the invention is the provision of a combined stile and corner grip member bent at its lower end in the form of a stirrup to provide a footstep immediately adjacent said corner stile member.

My invention further resides in certain other features of construction such as will be more fully pointed out hereinafter and claimed.

For further comprehension of my invention, reference may be had to the accompanying drawings wherein:

Figure 1 is a side elevational view of a box or house car having my improvements embodied therein, the central portion of the car being broken away.

Figure 2 is an enlarged sectional view showing the preferred method of securing the ladder rungs to the corner stile of the ladder structure, said section being taken on a line corresponding substantially to a line 2-2 of Figure 1.

Figure 3 is an end view of the box car shown in Figure 1 as viewed from right to left.

Figure 4 is a detail sectional view of the corner of the car illustrating the ladder structure and taken on a line corresponding substantially to a line 4-4 of Figure 3.

5 Figure 5 is a detail plan view of the corner of the car, showing the horizontal roof handholds in relation to the improved ladder structure.

10 Figure 6 is a side elevational view of a hopper dumping car, showing my improved ladder structure applied thereto, the central portion of the car being broken away.

15 Figure 7 is an end elevational view of the car shown in Figure 6, as viewed from right to left; and Figure 8 is an enlarged detail sectional view showing the method of securing the ladder stiles and ladder rungs of the embodiment shown in Figure 6, said view being taken on a line corresponding substantially to a line 8-8 of Figure 6.

20 Referring first to the embodiment illustrated in Figures 1 to 5 inclusive, my improvements are shown as applied to a car of the box or house type. In said drawings the usual average limiting clearance for freight cars is indicated by conventional dotted lines 10 and the rails on which the car stands are indicated at 11. Certain parts of the truck are indicated including the axles 12, wheels 13, journal box 14 and the journal box lid 15, the latter being also indicated in the open position as shown by dotted lines 16.

25 The body of the car as shown includes side walls 17, end walls 18, roof 19, longitudinal roof platform 20, transverse roof platform 21, roof handholds 22, push pole pocket 23, and hand brake platform 24.

30 The improved ladder structure proper in its preferred form includes side and end vertical stiles as indicated at A and B respectively, horizontal ladder rungs C and a vertical corner stile member D. The ladder stiles A and B are respectively adapted for application to the side and end of the car and are preferably formed of angle shaped sections each having one flange 25 thereof extending in parallelism with the related car side and the adjacent flange 26 extending inwardly towards the car wall, flange 25 of 35 the end stile B being preferably curved inwardly at its end as indicated at 125 in Figure 3 to prevent catching a man's clothing.

35 Each ladder rung member C is formed of substantially round rod and is preferably bent to a right angular formation to extend around the corner of the car thereby presenting rung sections 27 and 28 respectively adapted to extend along the side and end of the car. The outer ends of the rung sections 40 are forged to present flattened portions 29 whereby attachment is effected with flange 25 of the associated stile members A and B by rivets 30 or other suitable means. Each said rung member C has its corner portion 45 flattened and forged to present a flat face 31

extending for a limited distance diagonally across and merging into the respective angularly related rung sections 27 and 28 for the purpose of connecting with the ladder stile D in the manner to be hereinafter described.

50 The corner stile member D is preferably formed of a round rod of greater diameter than the rungs C and is recurrently flattened as indicated at 32 to present flat faces extending diagonally cornerwise between the respective rung sections and adapted to register with the flat faces 31 formed on the associated rungs C and attachment is there made between each said respective rung members and stile by a rivet 33 or other suitable fastening means, the rung being preferably disposed on the outer side of the stile member. At its lower end the corner stile member is extended downwardly below the level of the car side and is turned backwardly and upwardly upon itself in the form of a stirrup to afford a horizontally extending side footstep 34 and an inner upwardly and outwardly extending portion 35 which is flattened as indicated at 36 and there attached to the car side by a plurality of rivets 37 or other suitable fastening means. It is preferred to make the tread portion of the footstep of less length than the ladder rungs and this formation of the lower step, in connection with the advanced position of the ladder as a whole beyond the limit of the car side together with the placement of the footstep, in substantially the same vertical plane as said ladder, affords ample clearance for the journal box and permits the opening of the journal box lid to its full extent without fouling the footstep. This construction thus permits the use of a relatively short body overhang between the center of the truck and the end of the car.

55 At its upper end the combined corner stile and corner grip member is extended upwardly beyond the uppermost ladder rung C and deflected inwardly and diagonally above and in spaced relation to the roof, towards the roof handholds thus presenting a hand grip 38 at the upper end of the ladder, said grip section 38 in conjunction with the roof handholds thus providing an unbroken guiding means which extends from the footstep 34 to the roof of the car. The outer end of the inwardly directed hand grip 38 is secured to the car structure above the roof by a rivet as indicated at 39.

60 The respective side and end ladder stiles A and B are provided with upper and lower supporting brackets 40, said brackets being of angular shaped members having one flange 41 secured to the car wall and the adjacent flange 42 secured to the inwardly extending flange of the associated stile member. The combined corner stile and grip member D is provided with upper and lower brackets 43, each said bracket preferably being of gen-

ally Z-shape with outer and inner flanges 44 and 45 and an intervening web 46, said respective flanges 44 and 45 being secured to flattened portions 47 of the stile D and to the car structure respectively. The said supporting brackets effectively space the ladder structure from the car walls and provide ample clearance between the ladder rungs and vertical grip sections of the member D for the purpose of ensuring the safety of trainmen. In addition to the supporting brackets applied as heretofore described, it will be noted that the footstep in itself also serves as a bracket which helps to support the corner stile, which furthermore is also suspended at its upper end by means of the inturned grip portion 38 and in this manner a stable and very simple construction is attained. This arrangement of ladder structure permits assembling the ladder into a complete self-contained structure prior to its application to the car and it may then be quickly secured in position.

As is usual in car construction handholds 48 are provided on the ends of the car at the lower portion thereof, the ladders being arranged at diagonally opposite corners of the car. The two remaining corners are furnished with footstep 49 and a handhold 50 bent around the corner of the car to present side and end handhold sections as indicated at 51 and 52 respectively, said handhold being secured to the car structure at its opposite ends as at 53 and intermediately thereof by a bracket 54, the said footstep and handholds, as will be noted, being advanced beyond the end of the car to provide ample clearance for the adjacent journal box of the truck.

The embodiment shown in Figures 6, 7 and 8 is in all respects similar to the one heretofore described, with the exception that it shows the application of my improved ladder to an open top car and consequently is not provided with the inwardly extending upper grip section of the corner stile member. In the said drawings the car illustrated is of the hopper dump type having sloping end floors 110, end walls 111, side walls 112, having an inwardly offset portion 113 to accommodate the ladder rungs within the plane of the greatest car width. The usual sub-sidesill for this type of car is shown at 114, the end sill at 115, and push pole pocket 116 at the junction of said sills is indicated at 116.

Inasmuch as the ladder structure on the diagonally opposite corners and the footsteps and handholds on the opposite corners are of the same construction as that shown and described in connection with Figures 1 to 5, it is not deemed necessary to again describe the ladder and associated parts or to apply separate reference numerals thereto since the description heretofore given suffices equally

for the construction as applied to an open top dump car.

It will be obvious that my improved construction will greatly facilitate the work of trainmen in getting on or off cars inasmuch as vertical guide member and grip handle is present adjacent both side and end ladders and extends continuously from the foot-step to the upper extremity of the ladder, and the footstep, being formed integrally with the said stile member, is immediately adjacent the common stile thus permitting a trainman to move quickly from the step to the end ladder when it is necessary to reach the brake platform.

By flattening the corner stile at intervals to receive the flattened corner bends of the combined rungs, a very strong and rigid, and at the same time simple construction is afforded.

The ladder as a whole is one which may be readily made entirely from stock materials and by the utilization of a combined ladder stile and grip member having rung receiving portions therein, it will be obvious that a great measure of standardization between various types of cars may be obtained as the stile member provides the necessary vertical spacing for the ladder rungs and provides for the placement of both side and end ladder rungs on a common level.

While I have herein shown and described what I now consider the preferred manner of carrying out my invention, the same is merely illustrative and I contemplate all changes and modifications that come within the scope of the claims appended hereto.

I claim:

1. In combination with a car, a combined side and end ladder comprising flanged side and end stiles outstanding from the respective walls of the car, a rod like corner stile forming a vertical handhold outstanding from the corner of the car, and a plurality of combined rungs each comprising a side section and an end section in angular relation to one another, the ends of the side sections being secured to the flange of the side stile and the ends of the end sections being secured to the flange of the end stile, and the corner stile being provided with flattened portions spaced apart corresponding to the positions of the rungs affording attaching faces for the bends of the combined rungs, and attaching means for securing said bends to the corner stile.

2. In combination with a car, a combined side and end ladder comprising side and end stiles outstanding from the respective walls of the car, a corner stile outstanding from the corner of the car, and a plurality of combined rungs each comprising a side section and an end section in angular relation to one another, the ends of the side sections being secured to the side stile and the ends of the end sections being secured to the end stile,

and the corner stile being provided with flattened portions affording attaching faces for the bends of the combined rungs, and attaching means for securing said bends to the corner stile, the corner stile being extended at its lower end and bent rearwardly and upwardly and attached to the car to afford a foot step.

3. In combination with a car, a combined side and end ladder comprising side and end stiles outstanding from the respective walls of the car, a corner stile outstanding from the corner of the car, and a plurality of combined rungs each comprising a side section and an end section in angular relation to one another, the ends of the side sections being secured to the side stile and the ends of the end sections being secured to the end stile, and the corner stile being provided with flattened portions affording attaching faces for the bends of the combined rungs, and attaching means for securing said bends to the corner stile, the corner stile being extended at its upper end to afford a diagonally extending bracket portion secured to the roof of the car and constituting a hand grip.

4. In combination with a car, a combined side and end ladder comprising side and end stiles outstanding from the respective walls of the car, a corner stile outstanding from the corner of the car, and a plurality of combined rungs each comprising a side section and an end section in angular relation to one another, the ends of the side sections being secured to the side stile and the ends of the end sections being secured to the end stile, and the corner stile being provided with flattened portions affording attaching faces for the bends of the combined rungs, and attaching means for securing said bends to the corner stile, the corner stile being extended at its upper end to afford a diagonally extending bracket portion secured to the roof of the car and constituting a hand grip, and the lower end of the corner stile being downwardly extended below the floor of the car and turned inwardly and upwardly and attached to the car to afford a foot step.

5. In combination with a car, a combined side and end ladder comprising side and end stiles secured to the side and end walls of the car, a corner stile outstanding from the corner of the car, and a plurality of combined side and end rungs of angular formation having their ends secured respectively to the side and end stiles and having their bends secured to the corner stile, the corner stile being extended at its lower end and bent rearwardly and upwardly and attached to the car to afford a foot step.

6. In combination with a car, a combined side and end ladder comprising side and end stiles secured to the side and end walls of the car, a corner stile outstanding from the corner of the car, and a plurality of com-

bined side and end rungs of angular formation having their ends secured respectively to the side and end stiles and having their bends secured to the corner stile, the corner stile being extended at its upper end to afford a diagonally extending bracket portion secured to the roof of the car and constituting a hand grip.

7. In combination with a car, a combined side and end ladder comprising side and end stiles secured to the side and end walls of the car, a corner stile outstanding from the corner of the car, and a plurality of combined side and end rungs of angular formation having their bends secured to the corner stile, the corner stile being extended at its upper end to afford a diagonally extending bracket portion secured to the roof of the car and constituting a hand grip, and the lower end of the corner stile being downwardly extended below the floor of the car and turned inwardly and upwardly and attached to the car to afford a foot step.

8. As a new article of manufacture for railway cars, a combined side and end ladder having a series of ladder rungs disposed at an angle to each other, and a supporting stile common to both series of rungs, said stile at its upper end being angularly deflected inwardly to extend over the roof of the car for attachment thereto to form a hand grip common to both series of rungs.

9. As a new article of manufacture for railway cars, a combined side and end ladder having a series of ladder rungs disposed at an angle to each other, and a supporting stile common to both series of rungs, said stile at its lower end being formed to present a foot step and at its upper end being angularly deflected inwardly to extend over the car roof for attachment thereto to form a hand grip common to both series of rungs.

10. As a new article of manufacture for railway cars, a combined vertical hand hold and corner stile member for ladder rungs, said corner member being formed of a substantially round rod flattened at spaced intervals to present attaching faces for ladder rungs.

In witness that I claim the foregoing I have hereunto subscribed my name this 15th day of June 1928.

ARGYLE CAMPBELL.
